HERMETICALLY SEALED VESSEL

William J. Scott and William T. Cowhig, Rugby, England, assignors to General Electric Company, a corporation of New York

Application March 22, 1939, Serial No. 263,358
In Great Britain October 15, 1938

9 Claims. (Cl. 176—36)

This invention relates to hermetically sealed vessels and method of hermetically sealing such vessels, more particularly to envelopes of electric lamps, discharge devices or the like.

5 Where such vessels are evacuated or where the pressure within them is reduced considerably below atmospheric pressure, the hermetic sealing presents little difficulty since owing to the pressure within being less than that outside the device, when heat is applied to the glass tubulature through which the vessel is evacuated, the walls of the tube collapse as the glass softens. When, however, the pressure within the envelope or vessel approaches or exceeds atmospheric pressure 10 15 the operation of sealing is more difficult, as the walls of the tube will not collapse and may even expand outwardly when they are softened.

An object of the present invention is to provide an improved method and means for sealing vessels of the above type.

The invention utilizes a fusible part which extends within the interior of the vessel and which preferably, although not necessarily, constitutes a continuation of the tube through which 25 30 35 the vessel is exhausted. In accordance with the invention, the portion of the part which is within the vessel is softened by conduction, convection, radiation or by a combination of two or more of these methods. As a result of the fact that both the inner and outer surfaces of the part are subjected to substantially the same pressure, it may readily collapse when fused by this means to form a fused closure for the exhaust opening. If desired, mechanical pressure suitably applied to the fusible part may be used to assist the collapse of the part upon fusion.

For a more complete understanding of our invention, reference should be had to the accompanying drawing in which Fig. 1 is a sectional view of an electric lamp arranged for sealing according to our invention; Fig. 2 is a side elevational view of an electric lamp showing a re-entrant sealing tube positioned at a point other than in the lamp stem; Fig. 3 is a sectional view 40 45 50 of a lamp stem provided with a shield between the filament and a heater coil which is connected across the filament leads; and Fig. 4 is a sectional view of a lamp stem provided with an inductive heater illustrating a further embodiment of our invention.

Referring now to the drawing, Fig. 1 illustrates a lamp having a glass envelope 10 which may be evacuated or contain a gas at any desired pressure. Sealed into the base of this envelope is a stem 12 through which a tube 13 is

sealed. A portion 14 of the tube 13 extends into the interior of the envelope. Leading-in wires 15 also pass through the stem 12 and carry a filament 16 at their inner ends. In addition to these leading-in wires, a third wire 17 is sealed into the stem, and connected between this wire 17 and one of the leading-in wires 15 is a heating coil 18 which surrounds the tubular extension or re-entrant tube 14. After suitably adjusting the gaseous content of the vessel by the evacuation or filling thereof, the heating coil 18 is connected to a source of current through the leads 15 and 17 so that the glass tube 14 is heated up to its melting point and the end closes. If desired, the closure may be aided by mechanical pressure on the tube from a spring or weight. When the seal is completed, the tube 13 may be connected to a vacuum pump and sealed off at a point outside the envelope if desired.

In Fig. 2 we have shown a lamp in which a re-entrant tube 19 is secured to the envelope 10 on the opposite side of the bulb from the stem 12. Otherwise the arrangement is similar to that illustrated in Fig. 1.

In Fig. 3 we have shown a lamp stem 12 and filament 16 assembled for mounting in a bulb in which the heating coil 18, instead of being provided with a separate lead, is connected across the leading-in wires 15 which carry the filament 16. The heater 18 in this case is so designed as to dimensions and current-carrying capacity that it may be made to heat the tube 14 to the desired temperature during sealing but will burn out upon application of the voltage applied to the filament 16 during normal operation thereof, so that it does not short circuit the filament thereafter. In addition, a suitable shield 21, such as a sheet of mica, is provided between the filament 16 and heating coil 18 to protect the filament from damage during sealing.

In Fig. 4 we have shown a further modification of our invention in which means other than a heating coil is provided to fuse the glass re-entrant tube 14. Such means may comprise, for example, an element of sufficient conductivity to facilitate inductive heating thereof positioned in heat exchanging relation with the tube. The particular element shown comprises an inverted cup-like metal member 22 which is arranged to enclose the extremity of the tube 14 and which is supported thereon by a suitable element 23. When the envelope has been evacuated or filled to the desired pressure, the tube or cap is heated inductively by a high frequency

electromagnetic field so as to cause softening and fusion of the tube 14.

The heater coil in any of the modifications illustrated in Figs. 1 to 3 may be conveniently made of tungsten wire or a wire which may act as a getter, or the heating coil illustrated in any of these figures may be inductively heated. In the latter case it need not be connected across the leading-in wires, but may be supported from one only or may be wound around the re-entrant tube for support.

It will also be noted that in each case we have illustrated our invention with a glass sealing tube. It should be understood, however, that this tube need not be made wholly of glass but that its inwardly protruding end may be provided with a suitable sealing composition, such as an alloy of iron and chromium having substantially the same coefficient of expansion as the glass portion of the tube 14. The modifications shown in Figs. 3 and 4, of course, are intended to be used in vessels similar to the one illustrated in Fig. 1.

While we have shown particular embodiments of our invention, it will be understood, of course, that we do not wish to be limited thereto since many modifications may be made, and we therefore contemplate by the appended claims to cover any such modifications as fall within the true spirit and scope of our invention.

What we claim as new and desire to secure by Letters Patent of the United States is:

1. The method of preparing and sealing a vessel which comprises forming within the vessel an inwardly extending member having an opening therein, utilizing said opening to adjust the gaseous content of the vessel to a desired value, and thereafter applying heat to said member sufficient to fuse a portion of said member at a point within said vessel and thereby to seal said opening.

2. The method of preparing and sealing a vessel which comprises forming within the vessel an inwardly extending member having an opening therein, evacuating said vessel through said opening, and applying heat to said member sufficient to fuse a portion of said member at a point within said vessel and thereby to seal said opening.

3. The method of preparing and sealing a vessel which comprises forming within said vessel an inwardly extending member having an opening therein, filling said vessel with a charge of suitable gas through said opening, and applying heat to said member sufficient to fuse a portion of said member at a point within said vessel, thereby to seal said opening.

4. The combination in a gas tight vessel of means for adjusting the gaseous content of said vessel including a re-entrant member extending inwardly into the interior of said vessel, said member having an opening communicating therethrough with the exterior of said vessel, means for heating said re-entrant member at a point within said vessel to cause a portion of said member to collapse under the pressure of the gas surrounding it and fuse together thereby sealing said opening.

5. The combination in a gas tight vessel of means for adjusting the gaseous content of said vessel to a desired value comprising a re-entrant member extending inwardly into the interior of said vessel, said member having an opening com-

municating therethrough with the exterior of said vessel, fusible means for sealing said opening in said re-entrant member at a point within the interior of said vessel, and means for applying heat to said fusible means in said vessel thereby to seal said opening.

6. In a gas tight vessel having an electrical filament therein and a pair of leading-in conductors connected to said filament and extending through a wall of said vessel, the combination which includes means for adjusting the gaseous content of said vessel comprising a re-entrant member projecting into said vessel and having an opening therein, and means including a heater coil for applying heat to a portion of said re-entrant member sufficient to fuse it at a point within the interior of said vessel and thereby to seal said opening, said heater coil being connected to said leading-in wires and adapted to burn out upon application of the voltage to be applied to the filament during normal operation thereof.

7. In a gas tight vessel having an electrical filament therein and a pair of leading-in conductors connected to said filament and extending through a wall of said vessel, the combination which includes means for adjusting the gaseous content of said vessel comprising a re-entrant member projecting into said vessel and having an opening therein, means including a heater coil for applying heat to a portion of said re-entrant member sufficient to fuse it at a point within the interior of said vessel and thereby to seal said opening, said heater coil being connected to said leading-in wires and adapted to burn out upon application of the voltage to be applied to the filament during normal operation thereof, and protective means including a shield interposed between said heater coil and said filament.

8. In a gas tight vessel having an electrical filament therein and a pair of leading-in conductors connected to said filament and extending through a wall of said vessel, the combination which includes means for adjusting the gaseous content of said vessel comprising a re-entrant member projecting into said vessel and having an opening therein, and means for applying heat to a portion of said re-entrant member sufficient to fuse it at a point within the interior of said vessel, said last-named means including an element of sufficient conductivity to facilitate inductive heating thereof positioned in heat-exchanging relationship with said portion of said re-entrant member.

9. In a gas tight vessel having an electrical filament therein and a pair of leading-in conductors connected to said filament and extending through a wall of said vessel, the combination which includes means for adjusting the gaseous content of said vessel comprising a re-entrant member projecting into said vessel and having an opening therein, a heater coil for applying heat to a portion of said re-entrant member sufficient to fuse it at a point within the interior of said vessel and thereby sealing said opening, a third leading-in wire, said heater coil being connected to one of said pair of leading-in wires and to said third leading-in wire.
